BREATHING REGULATOR

John William Arpin, South Miami, Fla.

Application August 4, 1953, Serial No. 372,396

7 Claims. (Cl. 128—142)

1

This invention relates to breathing equipment and is particularly described in connection with a self-contained underwater breathing device.

The article of the instant invention comprises a breathing regulator which is used in conjunction with a source of breathable gas such as air. The regulator permits the inspiration of a required quantity of compressed air and provides means for exhaling exhaust air into the water.

Air intake regulators such as above described have been known in the art. However, to my knowledge they have embodied considerable disadvantages. For example, prior devices have been unduly complex and costly and they have embodied inherent limitations of operation as will hereinafter be described. In accordance with the instant invention, I provide a breathing regulator which is of pronounced simplicity relative to former devices while functioning in a superior manner. In one aspect of my invention, I have employed the force of compressed air or other gas which serves as the breathing medium, to operate a valve mechanism for admitting air into an equilibrium maintaining chamber where air is maintained under proper pressure. As far as I am aware, prior devices were required to oppose the force of the compressed air in operation of the regulator, whereas I employ such air as a positive force which governs the valve operation. This expedient simplifies the mechanism to a great extent since it eliminates heavy springs or the like which oppose the flow of air. Other portions of my regulator are novel and beneficial in that a slight and sensitive valve mechanism is used to control an air flow of great force.

Another aspect of my invention is that I facilitate breathing through my regulator without impeding or interfering with optimum operation of the device. Thus, it has been stated in the past that the exhaust valve must be positioned below or immediately adjacent to the operating diaphragm at all times in order to avoid a condition where the exhaust valve was uppermost and would represent such a lower level of pressure as to spontaneously draw the compressed air there-through and waste it. In order to correct this condition, the prior art has suggested placing the exhaust valve close enough to the diaphragm so that the pressure difference between them is less than the water pressure necessary to operate the valve through the diaphragm. While this expedient was operative, it placed an inherent limitation on the pressure necessary to operate the valve, such limitation depending upon the actual distance between the exhaust valve and the dia-

phragm. I am advised that divers have found regulators of the above type difficult to use in that they required forceful inhalations. As a consequence, they had decreased the force necessary to operate the diaphragm so that breathing through the regulator would be easier. However, this often brought about an adverse result because the exhaust valve might then be positioned too far away from the diaphragm for this new level of adjustment and loss of breathable gas would then ensue.

With the foregoing in mind, I have provided a regulator wherein the exhaust valve may be positioned anywhere therein, its distance from the diaphragm being of no moment. Furthermore, the regulator may be adjusted to operate at only the slightest pressure so that it is comfortable and convenient to the user. Notwithstanding such adjustment, no appreciable loss of breathable gas will take place through the exhaust valve. I have effected this result by preventing water pressure from acting directly on the exhaust valve when such exhaust valve is above the level of the diaphragm and might ordinarily cause a loss of gas. This I have accomplished by effectively interposing an air barrier between the water pressure and the exhaust valve in such a way that the water pressure which acts against the exhaust valve is more than that which acts against the diaphragm regardless of whether the exhaust valve is above or below the diaphragm.

The invention will be further understood from the following description and drawings in which:

Figure 1 is a diagrammatic view illustrating the assembly of the component units of a complete diving device;

Figure 2 is a top plan view of the regulator partly broken away;

Figure 3 is an enlarged cross-sectional view as taken along the line 3—3 of Figure 2;

Figure 4 is a fragmentary cross-sectional view illustrating the control valve position when connected upon by the fluid pressure diaphragm;

Figure 5 is a cross-sectional view as taken along the line 5—5 of Figure 3;

Figure 6 is a cross-sectional view as taken along the line 6—6 of Figure 3;

Figure 7 is a view taken along the line 7—7 of Figure 3; and

Figure 8 is a cross-sectional view as taken along the line 8—8 of Figure 5.

The source of gas is one or more cylinders containing the gas under pressure. For example, compressed air may be employed under a pres-

sure of more than approximately 2000 pounds per square inch. A strap or harness 11 serves to connect the cylinders to the body of the user. A valve 12 permits the air to be fed to the regulator 13. The regulator is provided with an intake pipe 14 and exhaust pipe 15. A corrugated rubber tube 17 extends from the intake pipe to the exhaust pipe and is formed with a central breathing inlet provided with a mouthpiece 18. The unit is generally used by strapping the cylinders to the back of the wearer so that the regulator 13 rests at the back of the neck. The tube 17 encircles the neck with the mouthpiece 18 held into the mouth. As is conventional, a mask covering both the eyes and the nose is worn.

Referring to Figure 3, the regulator 13 may be in the form of a flat cylinder and comprises a metal housing 19 which is formed with a lower chamber 20 and an upper chamber 21. A cover 22 caps the upper chamber 21 and clamps a rubber diaphragm 23 against a flange of the casing 19, such diaphragm separating and defining the upper and lower chambers. The diaphragm is reinforced at its center with a metal disk 24, the edges of the diaphragm being free to respond to pressure thereagainst from either direction.

When the device is used for underwater breathing, the water enters opening 25 of the cover 22 and acts upon the diaphragm 23 so as to depress it downwardly from the normal, planar position shown in Figure 3. Such downward depression of the diaphragm 23 in response to the water pressure is employed to actuate a valve which serves to restore the diaphragm to its normal, planar position by admitting air under pressure to the chamber 20, such air opposing the force of the water pressure. The valve is thus closed when the diaphragm is forced back by the air pressure. Accordingly, the air thus introduced into the chamber 20 will exactly equal the water pressure bearing against the outer face of diaphragm 23. Such valve action will now be described.

Valve 12 is initially opened to introduce the air under pressure to the regulator through the air inlet member 30. Air inlet member 30 is screwed to housing 19 and is formed with a central opening 31. Its upper face is formed with an annular depression 32 which serves as a high pressure chamber. It is connected by passage 33 to the opening 31. Centrally of high pressure chamber 32 is formed a series of passages 34 all of which communicate with the outlet passage 35. Such outlet passage 35, as will be hereinafter described, feeds the compressed air to the lungs of the user. Air inlet member 30 is suitably connected to the valve fittings of the tanks 10 by a clamp 36 which is secured to a flange 37 of the member 30.

Disposed flatly over the top face of air inlet member 30 is a control diaphragm 40. Diaphragm 40 is fabricated of rubber or the like and is formed with a small opening 41. Purely as an example, it has been found that an opening of .020" in diameter is satisfactory for the intended purposes as will be hereinafter described.

Seated upon diaphragm 40 is a valve seat member 42 which is formed with a central post 43. The bottom face of member 42 is formed with circular depression 44. Depression 44 provides an upper high pressure chamber in respect to chamber 32, being separated therefrom by diaphragm 40 and communicating therewith through opening 41. Disposed within chamber 44 is a screen 45 which is thin enough to permit the diaphragm

40 to rise into chamber 44 but without blocking off the central opening of post 43 as will be hereinafter described.

Post 43 is formed with a central opening 50 which communicates with chamber 44. Central opening 50 continues into the top face 51 of post 43, such top face 51 serving as a valve seat for valve cap 52. Valve cap 52 is formed with a skirt 53 which slidably embraces stem 43. Skirt 53 is formed with an outlet hole 54 which, in one position of the valve, communicates with central opening 50 and admits high pressure air into upper chamber 20. The valve 52 is normally urged into closing position against top face 51 by a spring 55. Member 42 is further formed with an upper collar 56 which threadedly receives an adjustable nut 57. Nut 57 bears against and compresses spring 55 so as to accordingly adjust the tension of the valve 52 against its seat, i. e. top face 51 of post 43. It will be evident that by screwing nut 57 inwardly, the normal valve closing tension may be increased and vice versa.

A lever 60 is provided with an end ring 61 which embraces the skirt 53 so as to be capable of lifting the valve 52 against the action of spring 55. Ring 61 is raised as illustrated by the broken lines of Figures 3 and 4 and it bears against the underside of flange 62 of valve 52. Accordingly, depression of the extreme end 63 of lever 60 causes the ring 61 to rise thereby lifting the valve 52 from its seat 51. This brings the openings 50 and 54 into communication so that compressed air may enter the chamber 20 and act against the underside of diaphragm 23 in opposition to the water pressure.

As will be hereinafter shown, diaphragm 23 responds to the user's inhalations so as to open the valve and feed air through the intake pipe 14. The tube 17 further provides an exhaust passage which is connected to exhaust pipe 15. Referring to Figure 2, exhaust pipe 15 is formed with a discharge outlet 70 to which is secured an exhaust valve 71. Exhaust valve 71 is of the rubber flapper type which is normally closed as illustrated in Figure 3 but which opens as air is forced therethrough.

The exhaust valve 71 is maintained in an exhaust chamber 72 which is distinct from the main diaphragm chambers 20 and 21. Pursuant to the principles of my invention as hereinafter described, the exhaust valve 71 may be disposed at any distance from the diaphragm 23 since the water pressure to which it is subjected will substantially always be at least that of the diaphragm 23. In effecting this result, the chamber 72 is formed with an outlet 73 which, in the form shown, is substantially at the level of cover 22. It is this outlet 73 which effects the results mentioned in preventing undue loss of waste of air while facilitating breathing by the user. Thus, the outlet 73 insures that the exhaust valve will be subjected to water pressure which is always at least that of the diaphragm 23 as long as the outlet 73 is disposed outwardly of the distance or spacing between the exhaust valve 71 and the diaphragm 23, such outward disposition being in the direction of diaphragm 23.

The operation of the regulator will now be described:

Assuming that the device is in operation under water, the diaphragm 23 is first depressed downwardly by the water pressure and, through lever 60, lifts the valve 52. Air from the tank has filled opening 31, passage 33, lower chamber 32 and opening 50 through diaphragm opening 41.

However, no flow of air has thus far been permitted since the valve 52 has been in closed position. When the valve 52 is lifted by the lever 60, the compressed air is permitted to flow through the passages above mentioned and through opening 54 into chamber 20. Air control hole or opening 50 is larger in diameter than opening 41. For example, when the opening 41 is .020" in diameter as above mentioned, the control opening 50 may be .030" in diameter. This produces a lower pressure in chamber 44 than in chamber 32 and the diaphragm 40 becomes displaced by rising or lifting accordingly. This action is illustrated in Figure 4 where it will be noted that the diaphragm 40 has risen although it may be further noted that it does not block off the control opening 50 because of the presence of screen 45. The lifting of diaphragm 40 permits the high pressure air from passage 33 and lower chamber 32 to enter the plural passages 34 and the main breathing passage 35. Such air is admitted into the intake pipe 14 and is breathed by the user through the tube 17 and mouthpiece 18. At the same time the high pressure air is permitted to flow up through a connecting passage 75 which opens into upper chamber 20 so that the main breathing passage 35 effectively communicates therewith.

It will be understood that the air in chamber 20 is of just enough pressure to offset the water pressure for the reasons above described. Accordingly, when the user inhales air from the pipe 14 and breathing pipe 17 such air is of a pressure which offsets the water pressure and the regulator therefor provides the correct air pressure for any depth.

Before each inhalation the diaphragms 23 and 40 are in their normal, planar state. When the user inhales, he draws air from chamber 20 through passages 75 and 35. This lowering of air pressure in chamber 20 causes the diaphragm 23 to deflect downwardly pursuant to the higher water pressure. The valve thereupon opens and the diaphragm 40 is lifted pursuant to the action above described and air is supplied from the source thereof through the passages 34 and opening 35 to the lungs of the user. The air will always equal the water pressure at any particular depth since otherwise the air will flow into the chamber 20, restore the diaphragm 23 to a planar state and cut off the feed valve.

It will be recognized from the foregoing that the pressure of the air source is employed positively to operate the valve mechanism. It will be further noted that the valve action is extremely simple and employs a minimum of parts while nevertheless controlling the great force represented by the compressed air.

A further advantage of the construction above described, is the fact that at no time during normal operation of the device will the exhaust valve 71 be at such a lower degree of pressure than the diaphragm 23 as to spontaneously cause air to be drawn therethrough and wasted. Thus, when the regulator is in its normal position illustrated in Figure 3, the exhaust valve 71 is far below the diaphragm 23 so that there will be no spontaneous sucking of air through the exhaust valve. It will be noted that in the position of Figure 1, when air is exhausted through valve 71, it will merely appear as bubbles which float out of the opening 73 as indicated by the arrows. Chamber 72 will be full of water at this time

so that the condition is just as if the exhaust valve 71 were free in the water.

When the regulator is turned upside down, as when a diver is swimming on his back or when he is diving or swimming downwardly, it might first appear that the exhaust valve 71 would then be at lower pressure than that of diaphragm 23 and would cause air to be drawn therethrough and wasted. However, as the diver exhales, the exhaled air will tend to rise and will soon fill the chamber 12. This would displace the water from chamber 72. The air will then serve as a buffer between the outside water and the valve 71 so that the pressure acting upon the valve 71 is that represented by the level of opening 73. It will be observed that the level of opening 73 is lower than that of diaphragm 23 when the device is inverted. Accordingly, whether the device is in its normal position as illustrated in Figure 3 or if it is completely reversed, the pressure acting against the exhaust valve 71 is always greater than that acting against the diaphragm 23. This prevents any waste of breathable air. This condition further allows the spring 55 to be adjusted to respond to the minimum drop in pressure of chamber 20. For example, it has been found that a two pound spring may be used with the control holes of the above specified diameters. As above stated, the reason why such a light spring may be used is that the proximity of the exhaust valve 71 to the diaphragm 23 is no longer a limiting factor on the sensitivity of the device when constructed according to the principles of my invention.

The valve 52 and valve seat member 40 may well be formed of plastic material such as nylon or polyethylene.

The device or the principal components thereof may be used in environments other than underwater, i. e. in any media wherein a breathing demand regulator may be required.

What is claimed is:

1. In a breathing device comprising a housing, a chamber in said housing, a first diaphragm mounted in said chamber, said diaphragm being flexible and being exposed to the surrounding fluid media through said housing whereby said diaphragm may be deflected by the pressure of the surrounding fluid media, an air inlet member on said housing, and means including a lever responsive to said deflection for admitting air under pressure through said air inlet member into said chamber so as to restore the diaphragm to a normal, undeflected position, an outlet passage on said housing for delivering compressed air from said inlet member to the lungs of a user, said means including a control diaphragm and an inlet member disposed below said control diaphragm and adapted to introduce compressed air to the underside of said control diaphragm, a lower chamber formed in said air inlet member directly below said control diaphragm, an air outlet formed in said air inlet member and communicating with said outlet passage, said control diaphragm normally closing said air outlet from said lower chamber, said control diaphragm being formed with an opening therethrough communicating with said lower chamber, said means further including a valve post member, a valve cap and a valve spring, said valve post member having a chamber in the bottom face thereof disposed over said control diaphragm so that said bottom face chamber constitutes an upper chamber for said control diaphragm, said valve post member having a central opening
2. The device as defined in claim 1, further including a lever member disposed in said housing and connected to said control diaphragm, said lever member being biased to move said control diaphragm into a deflected position.
3. The device as defined in claim 1, further including a lever member disposed in said housing and connected to said control diaphragm, said lever member being biased to move said control diaphragm into a deflected position.
4. The device as defined in claim 1, further including a lever member disposed in said housing and connected to said control diaphragm, said lever member being biased to move said control diaphragm into a deflected position.
5. The device as defined in claim 1, further including a lever member disposed in said housing and connected to said control diaphragm, said lever member being biased to move said control diaphragm into a deflected position.
6. The device as defined in claim 1, further including a lever member disposed in said housing and connected to said control diaphragm, said lever member being biased to move said control diaphragm into a deflected position.
7. The device as defined in claim 1, further including a lever member disposed in said housing and connected to said control diaphragm, said lever member being biased to move said control diaphragm into a deflected position.
8. The device as defined in claim 1, further including a lever member disposed in said housing and connected to said control diaphragm, said lever member being biased to move said control diaphragm into a deflected position.
9. The device as defined in claim 1, further including a lever member disposed in said housing and connected to said control diaphragm, said lever member being biased to move said control diaphragm into a deflected position.
10. The device as defined in claim 1, further including a lever member disposed in said housing and connected to said control diaphragm, said lever member being biased to move said control diaphragm into a deflected position.
11. The device as defined in claim 1, further including a lever member disposed in said housing and connected to said control diaphragm, said lever member being biased to move said control diaphragm into a deflected position.
12. The device as defined in claim 1, further including a lever member disposed in said housing and connected to said control diaphragm, said lever member being biased to move said control diaphragm into a deflected position.
13. The device as defined in claim 1, further including a lever member disposed in said housing and connected to said control diaphragm, said lever member being biased to move said control diaphragm into a deflected position.
14. The device as defined in claim 1, further including a lever member disposed in said housing and connected to said control diaphragm, said lever member being biased to move said control diaphragm into a deflected position.
15. The device as defined in claim 1, further including a lever member disposed in said housing and connected to said control diaphragm, said lever member being biased to move said control diaphragm into a deflected position.
16. The device as defined in claim 1, further including a lever member disposed in said housing and connected to said control diaphragm, said lever member being biased to move said control diaphragm into a deflected position.
17. The device as defined in claim 1, further including a lever member disposed in said housing and connected to said control diaphragm, said lever member being biased to move said control diaphragm into a deflected position.
18. The device as defined in claim 1, further including a lever member disposed in said housing and connected to said control diaphragm, said lever member being biased to move said control diaphragm into a deflected position.
19. The device as defined in claim 1, further including a lever member disposed in said housing and connected to said control diaphragm, said lever member being biased to move said control diaphragm into a deflected position.
20. The device as defined in claim 1, further including a lever member disposed in said housing and connected to said control diaphragm, said lever member being biased to move said control diaphragm into a deflected position.
21. The device as defined in claim 1, further including a lever member disposed in said housing and connected to said control diaphragm, said lever member being biased to move said control diaphragm into a deflected position.
22. The device as defined in claim 1, further including a lever member disposed in said housing and connected to said control diaphragm, said lever member being biased to move said control diaphragm into a deflected position.
23. The device as defined in claim 1, further including a lever member disposed in said housing and connected to said control diaphragm, said lever member being biased to move said control diaphragm into a deflected position.
24. The device as defined in claim 1, further including a lever member disposed in said housing and connected to said control diaphragm, said lever member being biased to move said control diaphragm into a deflected position.
25. The device as defined in claim 1, further including a lever member disposed in said housing and connected to said control diaphragm, said lever member being biased to move said control diaphragm into a deflected position.
26. The device as defined in claim 1, further including a lever member disposed in said housing and connected to said control diaphragm, said lever member being biased to move said control diaphragm into a deflected position.
27. The device as defined in claim 1, further including a lever member disposed in said housing and connected to said control diaphragm, said lever member being biased to move said control diaphragm into a deflected position.
28. The device as defined in claim 1, further including a lever member disposed in said housing and connected to said control diaphragm, said lever member being biased to move said control diaphragm into a deflected position.
29. The device as defined in claim 1, further including a lever member disposed in said housing and connected to said control diaphragm, said lever member being biased to move said control diaphragm into a deflected position.
30. The device as defined in claim 1, further including a lever member disposed in said housing and connected to said control diaphragm, said lever member being biased to move said control diaphragm into a deflected position.
31. The device as defined in claim 1, further including a lever member disposed in said housing and connected to said control diaphragm, said lever member being biased to move said control diaphragm into a deflected position.
32. The device as defined in claim 1, further including a lever member disposed in said housing and connected to said control diaphragm, said lever member being biased to move said control diaphragm into a deflected position.
33. The device as defined in claim 1, further including a lever member disposed in said housing and connected to said control diaphragm, said lever member being biased to move said control diaphragm into a deflected position.
34. The device as defined in claim 1, further including a lever member disposed in said housing and connected to said control diaphragm, said lever member being biased to move said control diaphragm into a deflected position.
35. The device as defined in claim 1, further including a lever member disposed in said housing and connected to said control diaphragm, said lever member being biased to move said control diaphragm into a deflected position.
36. The device as defined in claim 1, further including a lever member disposed in said housing and connected to said control diaphragm, said lever member being biased to move said control diaphragm into a deflected position.
37. The device as defined in claim 1, further including a lever member disposed in said housing and connected to said control diaphragm, said lever member being biased to move said control diaphragm into a deflected position.
38. The device as defined in claim 1, further including a lever member disposed in said housing and connected to said control diaphragm, said lever member being biased to move said control diaphragm into a deflected position.
39. The device as defined in claim 1, further including a lever member disposed in said housing and connected to said control diaphragm, said lever member being biased to move said control diaphragm into a deflected position.
40. The device as defined in claim 1, further including a lever member disposed in said housing and connected to said control diaphragm, said lever member being biased to move said control diaphragm into a deflected position.
41. The device as defined in claim 1, further including a lever member disposed in said housing and connected to said control diaphragm, said lever member being biased to move said control diaphragm into a deflected position.
42. The device as defined in claim 1, further including a lever member disposed in said housing and connected to said control diaphragm, said lever member being biased to move said control diaphragm into a deflected position.
43. The device as defined in claim 1, further including a lever member disposed in said housing and connected to said control diaphragm, said lever member being biased to move said control diaphragm into a deflected position.
44. The device as defined in claim 1, further including a lever member disposed in said housing and connected to said control diaphragm, said lever member being biased to move said control diaphragm into a deflected position.
45. The device as defined in claim 1, further including a lever member disposed in said housing and connected to said control diaphragm, said lever member being biased to move said control diaphragm into a deflected position.
46. The device as defined in claim 1, further including a lever member disposed in said housing and connected to said control diaphragm, said lever member being biased to move said control diaphragm into a deflected position.
47. The device as defined in claim 1, further including a lever member disposed in said housing and connected to said control diaphragm, said lever member being biased to move said control diaphragm into a deflected position.
48. The device as defined in claim 1, further including a lever member disposed in said housing and connected to said control diaphragm, said lever member being biased to move said control diaphragm into a deflected position.
49. The device as defined in claim 1, further including a lever member disposed in said housing and connected to said control diaphragm, said lever member being biased to move said control diaphragm into a deflected position.
50. The device as defined in claim 1, further including a lever member disposed in said housing and connected to said control diaphragm, said lever member being biased to move said control diaphragm into a deflected position.
51. The device as defined in claim 1, further including a lever member disposed in said housing and connected to said control diaphragm, said lever member being biased to move said control diaphragm into a deflected position.
52. The device as defined in claim 1, further including a lever member disposed in said housing and connected to said control diaphragm, said lever member being biased to move said control diaphragm into a deflected position.
53. The device as defined in claim 1, further including a lever member disposed in said housing and connected to said control diaphragm, said lever member being biased to move said control diaphragm into a deflected position.
54. The device as defined in claim 1, further including a lever member disposed in said housing and connected to said control diaphragm, said lever member being biased to move said control diaphragm into a deflected position.
55. The device as defined in claim 1, further including a lever member disposed in said housing and connected to said control diaphragm, said lever member being biased to move said control diaphragm into a deflected position.
56. The device as defined in claim 1, further including a lever member disposed in said housing and connected to said control diaphragm, said lever member being biased to move said control diaphragm into a deflected position.
57. The device as defined in claim 1, further including a lever member disposed in said housing and connected to said control diaphragm, said lever member being biased to move said control diaphragm into a deflected position.
58. The device as defined in claim 1, further including a lever member disposed in said housing and connected to said control diaphragm, said lever member being biased to move said control diaphragm into a deflected position.
59. The device as defined in claim 1, further including a lever member disposed in said housing and connected to said control diaphragm, said lever member being biased to move said control diaphragm into a deflected position.
60. The device as defined in claim 1, further including a lever member disposed in said housing and connected to said control diaphragm, said lever member being biased to move said control diaphragm into a deflected position.
61. The device as defined in claim 1, further including a lever member disposed in said housing and connected to said control diaphragm, said lever member being biased to move said control diaphragm into a deflected position.
62. The device as defined in claim 1, further including a lever member disposed in said housing and connected to said control diaphragm, said lever member being biased to move said control diaphragm into a deflected position.
63. The device as defined in claim 1, further including a lever member disposed in said housing and connected to said control diaphragm, said lever member being biased to move said control diaphragm into a deflected position.
64. The device as defined in claim 1, further including a lever member disposed in said housing and connected to said control diaphragm, said lever member being biased to move said control diaphragm into a deflected position.
65. The device as defined in claim 1, further including a lever member disposed in said housing and connected to said control diaphragm, said lever member being biased to move said control diaphragm into a deflected position.
66. The device as defined in claim 1, further including a lever member disposed in said housing and connected to said control diaphragm, said lever member being biased to move said control diaphragm into a deflected position.
67. The device as defined in claim 1, further including a lever member disposed in said housing and connected to said control diaphragm, said lever member being biased to move said control diaphragm into a deflected position.
68. The device as defined in claim 1, further including a lever member disposed in said housing and connected to said control diaphragm, said lever member being biased to move said control diaphragm into a deflected position.
69. The device as defined in claim 1, further including a lever member disposed in said housing and connected to said control diaphragm, said lever member being biased to move said control diaphragm into a deflected position.
70. The device as defined in claim 1, further including a lever member disposed in said housing and connected to said control diaphragm, said lever member being biased to move said control diaphragm into a deflected position.
71. The device as defined in claim 1, further including a lever member disposed in said housing and connected to said control diaphragm, said lever member being biased to move said control diaphragm into a deflected position.
72. The device as defined in claim 1, further including a lever member disposed in said housing and connected to said control diaphragm, said lever member being biased to move said control diaphragm into a deflected position.
73. The device as defined in claim 1, further including a lever member disposed in said housing and connected to said control diaphragm, said lever member being biased to move said control diaphragm into a deflected position.
74. The device as defined in claim 1, further including a lever member disposed in said housing and connected to said control diaphragm, said lever member being biased to move said control diaphragm into a deflected position.
75. The device as defined in claim 1, further including a lever member disposed in said housing and connected to said control diaphragm, said lever member being biased to move said control diaphragm into a deflected position.

formed therethrough adapted to communicate with said first named housing chamber when said first named diaphragm is deflected, said post central opening communicating with said upper chamber and said control diaphragm opening, said valve cap normally closing said valve post opening from said first named housing chamber, and said valve spring acting against said valve cap for normally closing said valve post opening, the deflection of said first named diaphragm actuating said lever so as to displace said valve cap against the action of said spring, a further air passage being formed between said outlet passage and said first named housing chamber.

2. An article according to claim 1 and wherein said control diaphragm opening is of lesser diameter than said valve post central opening whereby air flowing through said openings will tend to elevate said control diaphragm into said upper chamber so as to establish communication between said air inlet member and said outlet passage.

3. In a breathing regulator comprising a housing, a diaphragm in said housing, said diaphragm being flexible and being exposed to the surrounding fluid media through said housing whereby said diaphragm may be deflected by the pressure of surrounding fluid media, and means including an inlet member responsive to said deflection to admit air under pressure through said inlet member and into said housing, outlet passage means including a discharge outlet on said housing for exhausting exhalations into said surrounding media, an exhaust valve connected to said discharge outlet, an exhaust chamber secured to said housing and in which said exhaust valve is disposed, said exhaust valve being spaced from said diaphragm, and said exhaust chamber being formed with an air outlet which is outside of the spacing between said diaphragm and said exhaust valve in the direction of said diaphragm and which is at least at the level of said diaphragm and said exhaust chamber being otherwise totally enclosed.

4. In a breathing regulator comprising a housing, a diaphragm in said housing, said diaphragm being flexible and being exposed to the surrounding fluid media through said housing whereby said diaphragm may be deflected by the pressure of surrounding fluid media, and means including an inlet member responsive to said deflection to admit air under pressure through said inlet member and into said housing, outlet passage means including a discharge outlet on said housing for exhausting exhalations into said surrounding media, an exhaust valve connected to said discharge outlet, an exhaust chamber secured to said housing and in which said exhaust valve is disposed, said exhaust chamber being formed with an outlet which is on an opposite side of said diaphragm from said exhaust valve and being otherwise totally enclosed.

5. In a breathing regulator comprising a housing, a diaphragm in said housing, said diaphragm being flexible and being exposed to the surrounding fluid media through said housing whereby said diaphragm may be deflected by the pressure of surrounding fluid media, and means including an inlet member responsive to said deflection to admit air under pressure through said inlet member and into said housing, outlet passage means including a discharge outlet on said housing for exhausting exhalations into said surrounding media, an exhaust valve connected to said discharge outlet, an exhaust chamber secured to said housing and in which said exhaust valve is disposed, said exhaust valve being normally closed and adapted to be opened by the exhalations of the user, said exhaust valve being vertically spaced from said diaphragm in a normal position of said housing, said exhaust chamber being formed with a single outlet which is vertically spaced from said diaphragm in an opposite direction from said exhaust valve.

6. An article according to claim 5 and wherein said exhaust chamber outlet is also laterally spaced from said diaphragm.

7. In a breathing regulator comprising a housing, a diaphragm in said housing, said diaphragm being flexible and being exposed to the surrounding fluid media through said housing whereby said diaphragm may be deflected by the pressure of said surrounding fluid media, and means including an inlet member responsive to said deflection to admit air under pressure through said inlet member and into said housing, outlet passage means including a discharge outlet on said housing for exhausting exhalations into said surrounding media, an exhaust valve connected to said discharge outlet, an exhaust chamber secured to said housing and in which said exhaust valve is disposed, said exhaust valve being vertically spaced from said diaphragm, and said exhaust chamber being formed with an air outlet which is at least at the vertical level of said diaphragm when the regulator is in a position where the diaphragm is at a higher vertical level than said exhaust valve, and said exhaust chamber being otherwise totally enclosed below the vertical level of said air outlet and below the vertical level of said diaphragm.
